UNITED STATES PATENT OFFICE.

CHRISTOPHER OFFENHAUSER, OF PHILADELPHIA, PENNSYLVANIA.

DRIER.

Application filed May 25, 1922. Serial No. 563,528.

One object of my invention is to provide a relatively simple, substantial and practical machine for drying, cooking or rendering such materials as the animal waste from packing houses, so that the water and volatile ingredients shall be removed and the dried or cooked residue be left in a form available for feeding to cattle, poultry and the like.

10 Another object of the invention is to provide a drying or cooking machine of the above type whose construction shall be such as to permit the convenient regulation of the temperature at which it is operated and 15 the drawing off of certain valuable materials such as tallow, which separate out under operating conditions; the construction being such that the removal of these substances may be accomplished without interfering 20 with the operation of the machine.

A further object of the invention is to provide a machine of the type above noted with novel means for collecting and continuously withdrawing the objectionable 25 gases or vapors which may be generated, so that these may be conducted to a suitable washer or place of discharge.

These objects and other advantageous ends I attain as hereinafter set forth, reference being had to the accompanying drawings, in which,

Fig. 1 is a longitudinal vertical section of a machine constructed in accordance with my invention;

35 Fig. 2 is an elevation of one end of the machine shown in Fig. 1;

Fig. 3 is a vertical section on the line 3—3, Fig. 1;

40 Figs. 4 and 5 are respectively a longitudinal vertical section and an end elevation of a modified form of my invention; and

Fig. 6 is a vertical section on the line 6—6, Fig. 4;

45 Fig. 7 is a detailed section of one of the trunnions as seen from the line 7—7 of Fig. 1.

In Figs. 1 to 3 inclusive of the above drawings, 1 and 2 represent the end portions of a supporting frame or other suitable structure respectively carrying bearings 3 and 4 for the journals 5 and 6 at the ends of a

horizontally extending, more or less elongated rotary drum 7. The latter is provided with a steam jacket 8 and its heads 9 and 10 are respectively fixed to flanges connected to 55 or formed as part of said two journals 5 and 6. This drum is rotated by any suitable means and in the present instance I have illustrated it as having fixed to one end a gear ring 11 driven from a suitable pinion 60 (not shown) on a shaft 12 mounted in bearings on the frame 1 and receiving power from any suitable source through a pulley 13. For supplying steam to the jacket 8, the journal 6 and its flange carrying the head 65 10, are provided with any suitable number of passages 14, which extend in the journal in lines substantially parallel to the axis of the drum and then run radially outward in the flange. At the outer edge of the latter 70 said channels are connected by conduits or other suitable means 15 with the space constituting the steam jacket between the inner and outer walls of the drum. The opposite ends of these channels 14 are carried or extend into a flat plate 16 at the outer end of the journal 6 where they open on opposite sides of and equi-distant from the center line or axis of rotation of said journal.

Adjacent the end plate 16 of the journal 80 is an elongated fixed structure 17 having a flat face engaging with said plate and formed with two passages or ports periodically brought into connection with the passages 14 in the journal as this is rotated, 85 there being a steam supply pipe 18 connected to one of these ports and an exhaust pipe 19 connected to the other. A suitable stuffing box 20 is mounted between the structure 17 and the adjacent part of the rotating head 90 or end plate 16 so as to prevent the escape of steam therebetween.

The parts are so arranged that when the drum 7 occupies the position in which one of its conduits 15 is in the lowest part of its 95 path of movement and therefore in position to receive any liquid which may have condensed in the steam jacket, another one of said conduits is uppermost and is connected through a passage 14 and the upper one of 100 the ports in the structure 17 with the steam supply pipe 18. The lowermost one of the

conduits 15 is then in connection with the exhaust or waste pipe 19 so that steam delivered through the pipe 18 not only heats the steam jacket, but acts on any water which 5 may collect in the bottom of the same to blow it out through the exhaust pipe. Obviously this operation occurs periodically during the rotation of the drum and there 10 may be any desired number of pairs or sets of the pipes and passages 14.

Within the two journals 5 and 6 are mounted the tubular supporting trunnions 21 and 22 of an inner fixed drum 23 coaxially positioned within the main drum 7 and 15 held immovable in said journals in any suitable manner. Agitating or lifting shelves 24 are mounted within the main drum 7 so as to raise or tumble material therein and these carry a suitable number of scrapers 25 20 positioned to act upon the cylindrical exterior surface of the fixed drum 23 as the outer drum is rotated. The latter drum is shorter than the main drum, which at one end is provided with a transverse perforated 25 partition or screen 26 forming a narrow chamber within which a vapor delivery pipe 27 extends radially upward from the trunnion 21 with whose interior its lower 30 end communicates. The upper end of this conduit is open so that water vapor or any gases generated by or given off from the material being treated can freely pass into it through the partition 26 which obviously prevents the entrance of solid material.

35 The outer end of the trunnion 21 is connected to a delivery pipe 28 leading to a stack or washer and exhaust fan as desired, whereby the vapors or gases given off are effectually disposed of. The fixed drum 23 is 40 internally heated by steam delivered through a supply pipe 29 in the trunnion 21, and any water condensed in said drum is withdrawn through an exhaust pipe 30 also extending through said trunnion. The latter in addition carries a suction pipe 31 whose inner 45 end extends from the trunnion radially downward to a point adjacent the bottom of the main drum 7, while its opposite end is connected to any suitable device for withdrawing liquids, such as tallow or melted 50 fat, which may be rendered from the material under treatment and pass through the partition 26 into the collecting chamber at the end of the drum.

55 Suitable manholes or doors (not shown) are provided in the cylindrical wall of the main drum 7 to permit of the introduction and removal of material, and under operating conditions said drum, after having been charged with packing house waste for example, is rotated at a rate say of two revolutions a minute. At the same time steam is supplied to the pipes 18 and 29 so that both the inner and the main drums are heated;— 60 it being understood that the pressure of said

steam is such and the amount delivered is so regulated, that the material under treatment is cooked or dried at the desired temperature. As the drum 7 is turned, the shelves 24 raise and then drop the material, some of which falls upon the drum 23 so that it is thoroughly agitated and stirred while heat is applied in the best manner to drive off the water, melt the fat and also cook the solid substances. 75

Any material tending to stick to the external surface of the drum 23 is effectually and continuously removed by the scrapers 25 and any water of condensation is forced out of the inner drum as well as out of the 80 steam jacket by the means illustrated. Any water vapor or gases given off by the material in the drum 7 are drawn out through the vapor pipe 27 and from time to time the liquefied fat, etc., collecting in the bottom 85 of the main drum 7 and passing through the partition 26, is withdrawn through the pipe 31.

If desired, the inner drum may be made fast to and rotated with the main drum, as 90 indicated in Figs. 4 to 6 inclusive, in which case said inner drum 23^a, is fastened at one end to one of the heads of the main drum and at the opposite end is supported by the 95 perforated partition 26. In this case the steam for heating the inner drum is obtained from the steam jacket 8 through two or more pipes 40, which also serve to conduct any water of condensation from said inner 100 drum into the steam jacket of the main drum, from which it is ultimately delivered as previously described, through the pipes 15 and 19.

I claim:

1. The combination in a drier, of a main 105 rotary drum having trunnions; a transverse perforated partition mounted in the drum to form a relatively small collecting chamber; a second stationary drum coaxially positioned within the main drum outside of 110 said chamber; means for introducing steam into the second drum; and a pipe extending through one of the trunnions of the main drum for withdrawing liquid collecting in 115 said chamber.

2. The combination in a drier, of a rotary 120 drum having a steam jacket; a trunnion on each end of the drum; conduits extending through one of the trunnions and connected to the steam jacket; a transverse, perforated partition near one end of the drum forming a narrow chamber; a heating drum located in the main portion of the rotary drum; means for supplying steam to the heating 125 drum; lifting shelves on the main drum; scrapers bearing upon the outer surface of the heating drum; a conduit for withdrawing liquid collecting in the chamber formed by the perforated partition; and a vapor delivery pipe communicating with the upper 130

portion of said chamber and extending through one of the trunnions of the drum.

3. The combination in a drier of a rotary drum having a steam jacket; trunnions for 5 rotatably supporting said drum; conduits extending through one of the trunnions and connected to the steam jacket; relatively

fixed supply and exhaust conduits positioned to be periodically connected to said conduits of the trunnion as the drum is rotated; with 10 a stationary drum having supporting portions extending in the trunnions of said rotary drum.

CHRISTOPHER OFFENHAUSER.
